UNITED STATES PATENT OFFICE.

CHARLES PIEZ, OF CHICAGO, ILLINOIS, ASSIGNOR TO LINK-BELT COMPANY, OF CHICAGO,
ILLINOIS, A CORPORATION OF ILLINOIS.

APPARATUS FOR QUENCHING, SCREENING, AND LOADING COKE.

1,206,588.

Specification of Letters Patent. Patented Nov. 28, 1916.

Application filed May 8, 1912. Serial No. 696,005.

To all whom it may concern:

Be it known that I, CHARLES PIEZ, a citizen of the United States, residing in Chicago, county of Cook, State of Illinois, have invented certain Improvements in Apparatus for Quenching, Screening, and Loading Coke, of which the following is a specification.

The object of this invention is to construct an apparatus to be located at the discharge end of a bank of coke ovens. Said apparatus receives the coke as it is discharged from the ovens, quenches it and finally discharges it; the coke being screened as it is transferred to the cars.

In the accompanying drawings: Figure 1, is a plan view of my improved apparatus; Fig. 2, is a side view; Fig. 3, is a transverse section on the line 3—3, Fig. 1, of the coke oven; illustrating the car and moving platform in elevation; and Fig. 4, is a transverse section through the car and platform.

Referring to the drawings, A are the ovens of the ordinary type, having the coking chambers *a*. At the end of these chambers are discharge openings *a'*, having doors. The coke is discharged from the chamber *a* through these doorways.

B is a car having trucks *b*; the wheels 30 of which travel on rails *c* on the elevation in front of the ovens A. On the frame *B'* of this car B are longitudinal beams *B*², in the present instance, on which are the bearings for the supporting rollers 35 *b'* for the moving platform D. This platform has rails *d* on the under side, which rest upon the rollers; the rollers being flanged so as to properly guide the rails and thus hold the moving platform laterally in 40 position. On the under side of the platform are two longitudinal racks *e*—*e* and mounted in bearings on the frame *B'* of the car is a power shaft *E* on which are pinions *e'*, which mesh with the racks. These pinions 45 are driven by any suitable means under the control of the operator in the cab F, located on the car at one side of the moving platform.

The car can be shifted in front of any one 50 of the ovens and the moving platform can be moved longitudinally on the car as the coke is discharged from the oven. Extending transversely above the moving platform D are sprinkling devices G, consisting of a 55 main pipe *g* and branches *g'*. These

branches may be of any length desired so as to form a spray sufficient to properly quench the coke as it passes under the spraying device when the platform is moved. Projecting from one side of the car body *B'* is a frame *H* on which is mounted a screen *I*. This screen is arranged at an angle and consists of a series of bars *i* and at the discharge end of the screen is an undercut valve *h* of any of the usual types.

I preferably reciprocate the screen and thus the screen need not be arranged at so deep an angle as a fixed screen. In the present instance, I have shown a crank shaft *n* having a rod *n'* connected to the screen; the screen shaft being driven by any suitable means.

Directly under the screen is a dust hopper having a valve *m* to allow for the discharge of dust as it accumulates in the hopper. At the side of the elevation, but at a lower level is a track *P* for the cars on to which the coke is to be delivered. The cars *S* have wheels *s* adapted to rails *p*—*p*, as shown.

In order to discharge the coke from the moving platform over the screens into the cars, I provide a plow *W*, pivoted at *w* at one end of the screen. The plow can be moved on its pivot over the surface of the moving platform to remove a portion of the coke or the entire body of coke which has accumulated on the platform. The face of this plow may be of any shape desired, either straight, as shown, or curved, if found preferable.

The operation of the mechanism is as follows: When it is desired to discharge the coke from one or more ovens, the forward end of the platform D is brought in line with the oven to be discharged and when the discharge apparatus forces the coke from the oven, the platform D is moved simultaneously with the discharge, while the car remains stationary and at the same time water is discharged from the quenching device onto the platform. Consequently, the coke, as it is discharged from the oven, is spread on the platform and passes under the quenching device. The coke after it passes the quenching device is cooled by the action of the water and if the platform be only of sufficient length to receive the contents of one oven, then, after this oven is discharged, the plow *W* is moved into a position to act so that upon the reversal of the

movement of the platform the coke will be removed from the platform and discharged laterally over the reciprocating screen I, if this type of screen is used, and into the car S 5 located under the screen.

Either the car S may be moved so as to be properly located or the car B, carrying the platform D, may be moved. After one car has been loaded, another car may be 10 shifted into position to receive the material remaining on the platform. If the platform is of such a length as to receive the contents of two or more ovens, then the platform can be moved part-way to receive the discharge 15 of one oven and during the remainder of the movement can receive the contents of another oven.

It will be seen that the length of the platform will depend considerably upon the size 20 of the coke ovens. If there be sufficient time between the discharge of one oven and the discharge of another oven, then the coke may remain on the platform to cool before being discharged into the cars.

25 I claim:

1. The combination in a series of coke ovens having the discharge openings at one end, of a track extending along the front of the ovens; a car arranged to travel on the 30 track so as to be moved in front of any one of the ovens; a longitudinally moving platform on the car; means for moving the platform so that as the platform is moved past the discharge end of the coke oven, while the 35 coke is being discharged, the coke will be distributed over the platform.

2. The combination in an apparatus for quenching, screening and loading coke, of a series of coke ovens having their discharge 40 openings at the same end; a track located at the discharge ends of the coke ovens and extending parallel with the faces of the ovens and below the discharge openings; a car arranged to travel on the track so as to be placed in front of any one of the ovens; a 45 platform mounted on the car and arranged to move longitudinally thereon; a fixed quenching device on the car and extending

over the platform, said platform arranged to receive coke from an oven in front of 50 which the car is located; and means for longitudinally moving the platform independently of the car so that the platform is moved at a given speed as the coke is discharged from the oven in order that it will 55 be spread on the platform and, as the movement of the platform continues, the coke will pass under the quenching device and be quenched.

3. The combination in an apparatus for 60 quenching, screening and loading coke, of a series of coke ovens having their discharge openings at the same end; a track located at the discharge ends of the coke ovens and extending parallel with the faces of the 65 ovens and below the discharge openings; a car arranged to travel on the track so as to be placed in front of any one of the ovens; a platform mounted on the car and arranged to move longitudinally thereon; a fixed 70 quenching device on the car and extending over the platform, said platform arranged to receive coke from an oven in front of which the car is located; means for longitudinally moving the platform independently 75 of the car so that the platform is moved at a given speed as the coke is discharged from the oven in order that it will be spread on the platform and, as the movement of the platform continues, the coke will pass under the quenching device and be quenched; a plow pivoted at one side of the car and arranged to extend diagonally over the platform; and a chute at the side of the car in line with the plow so that after the platform 80 has moved forward and receives the coke the discharge plow can be moved so as to discharge the coke laterally from the platform on its return movement.

In testimony whereof, I have signed my 85 name to this specification, in the presence of two subscribing witnesses.

CHARLES PIEZ.
